DESIGN FOR A DISPLAY STAND

Daniel Marovich, Oakland, Calif., assignor to National Foundation for Infantile Paralysis, New York, N. Y.

Application March 20, 1942, Serial No. 106,268

Term of patent 3½ years

To all whom it may concern:

Be it known that I, Daniel Marovich, a citizen of the United States, residing at Oakland, in the county of Alameda and State of California, have invented a new, original, and ornamental Design for Display Stands, of which the following is a specification, reference being had to the accompanying drawing, forming a part thereof.

on a reduced scale.

I claim:

The ornamental design for a display stand,
substantially as shown.
